Fig. 11

Fig. 12

FIG. 1 is a perspective view of a water ski embodying my design;

FIG. 2 is a side elevation thereof, both sides being the same;

FIG. 3 is a rear end elevation thereof;

FIG. 4 is a top plan view thereof;

FIG. 5 is a bottom plan view thereof;

FIG. 6 is a front end elevation thereof;

FIG. 7 is a perspective view of a modified form thereof;

FIG. 8 is a side elevation of the modified form thereof, both sides being the same;

FIG. 9 is a rear end elevation of the modified form thereof;

FIG. 10 is a top plan view of the modified form thereof;

FIG. 11 is a bottom plan view of the modified form thereof; and

FIG. 12 is a front end elevation of the modified form thereof.

I claim:

The ornamental design for a water ski, as shown and described.
